UNITED STATES PATENT OFFICE.

ELMER V. CHRISTIANA, OF KINGSTON, NEW YORK.

VICE FOR HOLDING VEHICLE-LAMPS.

1,016,914.

Specification of Letters Patent. Patented Feb. 6, 1913.

Application filed July 15, 1911. Serial No. 638,715.

To all whom it may concern:

Be it known that I, ELMER V. CHRISTIANA, a citizen of the United States, and a resident of Kingston, in the county of Ulster and State of New York, have invented new and useful Improvements in Vises for Holding Vehicle-Lamps, of which the following is a specification.

My invention relates to brackets or vises 10 for holding automobile and carriage lamps while being polished or repaired.

The object of my invention is to produce a bracket of said character which may be adjusted to accommodate lamps of different 15 types and sizes, and by which same may be held in different positions for the convenience of the workman.

A further object thereof is to produce a more simple, cheap and efficient article of 20 said class than has heretofore been provided.

To these ends, my invention includes the combinations and arrangement of component parts to be hereinafter described and 25 more particularly pointed out in the claim.

In the accompanying drawings illustrating my invention in which like reference characters indicate similar parts, Figure 1 is a perspective view of my invention in 30 use; Fig. 2 is a similar view with the lamp detached, and Fig. 3 is a plan view of the same.

Referring to the drawings, 1 indicates a base, preferably of metal rigidly secured 35 upon a work bench or other support, and provided with the vertical screw-threaded stud 2. Mounted upon said stud, I provide the diametrically opposed bowed brackets or arms 3 and 4, and the lateral arm 5 secured thereon by the thumb-nut 6. Said arms 3 and 4, as shown, comprise the horizontal portions 3^a and 4^a, the upright bowed portions 3^b and 4^b, and terminate in the heads 3^c and 4^c which are pierced transversely to accommodate the hooks 7 and 8 45 hereinafter described. The horizontal portions 3^a and 4^a of said arms are provided with longitudinal slots 3^d and 4^d through which the threaded stud 2 projects and on 50 which they are clamped by the nut 6. From such construction it will be apparent that

such arms may be adjusted outwardly and inwardly to regulate the distance between themselves to be accommodated to different sizes of lamps to be held thereon.

The hooks 7 and 8 are provided with screw-threaded outer horizontal ends 7^a and 8^a passing through the orifices in the heads 3^c and 4^c and are clamped therein by the nuts 9 and 10, the inner angle ends 7^b and 8^b 60 extending inwardly toward each other to engage the orifices provided on lamps by which same are secured on a vehicle. It will also be appreciated that a lamp secured on said hooks will be suspended between the 65 bowed upright portions of the bracket or arms 3 and 4 in which position it is conveniently held for a workman, and that said hooks may be turned in their sockets to adjust the position of the lamp and securely 70 held by the nuts 9 and 10.

The lateral arm 5 is rigidly secured on the base 1, and is provided at its outer end with a vertical threaded stud 11 on which are pivoted the hooks 12 and 13 through the 75 orifices in their lower ends, and clamped thereon by the nut 14. Said hooks 12 and 13 are adapted to engage and hold the smaller or "tail" lamps of a vehicle, and may be adjusted to different sizes by turning on their pivot and securely clamped by the nut 14.

Having thus described my invention, what I claim as new and desire to be secured by Letters Patent, is—

The combination with a base, of laterally adjustable oppositely arranged arms mounted thereon comprising horizontal portions having upwardly extending portions provided with enlarged and transversely 90 pierced outer ends, L-shaped brackets carried in the enlarged pierced outer ends of the arms the inner ends of which are adapted to be rotated in a vertical plane, and means for clamping the brackets in fixed adjustment on the arms to support a vehicle lamp in adjusted positions, substantially as described.

ELMER V. CHRISTIANA.
